UNITED STATES PATENT OFFICE.

CASWELL LEE LEONARD, OF CORINTH, MISSISSIPPI.

FOLDING CRATE FOR EGGS AND OTHER PRODUCTS.

1,401,993.

Specification of Letters Patent.

Patented Jan. 3, 1922.

Application filed February 27, 1920. Serial No. 361,615.

To all whom it may concern:
Be it known that I, CASWELL LEE LEONARD, a citizen of the United States, residing at Corinth, in the county of Alcorn and 5 State of Mississippi, have invented certain new and useful Improvements in Folding Crates for Eggs and other Products, of which the following is a specification, reference being had therein to the accompanying 10 drawing.

This invention relates to shipping crates, and has for its object the provision of a novel and improved folding crate for shipping eggs and other products, which can 15 be collapsed flat so as to be stored or returned within small compass, thereby saving space and transportation cost.

Another object is the provision of such a 20 crate constructed of sheet metal having its walls and top and bottom hingedly connected in a novel manner, to fold together compactly, and to afford rigidity when the crate or box is unfolded and erected, the arrangement being such that the crate will withstand 25 the wear and tear to which it is subjected in use.

A still further object is the provision of 30 novel hinge connections between the walls whereby they can be folded together with the usual foldable egg cells or fillers therein, and said walls being provided with means for retaining said fillers therein, especially when the crate is folded.

It is also the object of the invention to 35 provide such a crate which can be manufactured conveniently and cheaply from sheet metal and which will be thoroughly practical and efficient in use.

With the foregoing and other objects in 40 view, which will be apparent as the description proceeds, the invention resides in the construction and arrangement of parts hereinafter described and claimed, it being understood that changes can be made within 45 the scope of what is claimed without departing from the spirit of the invention.

The invention is illustrated in the accompanying drawings, wherein:

Figure 1 is a perspective view of the crate 50 when empty, and the top swung open.

Figs. 2 and 3 are vertical sections of the 55 crate at right angles to one another, portions being broken away, and Fig. 3 showing the top and bottom swung open in dotted lines.

Fig. 4 is a plan view showing the crate partly folded.

As shown, the crate or box is in the form of a cube although it can be of various rectangular shapes and sizes. The crate comprises the sheet metal front wall 6, rear wall 7, side walls 8 and 9, top 10 and bottom 11. The adjacent vertical edges of the front wall 6 and side wall 9 are hingedly connected, as at 12, and the adjacent vertical edges of the back wall 7 and side wall 8 are similarly hinged, as at 13, said hinges coinciding with the corresponding diagonally opposite corners of the crate. The opposite vertical edge of the front wall 6 60 has a flange or portion 14 extending rearwardly at right angles, and hingedly connected, as at 15, to the forward vertical edge of the side wall 8, and, similarly, the vertical edge of the rear wall 7 opposite to the hinge 13 has a flange or portion 16 extending forwardly at right angles and hingedly connected, as at 17, with the rear vertical edge of the side wall 9. The hinges 15 and 17 are therefore located short distances 65 away from the corresponding corners of the crate, whereby when the walls are folded together, as suggested in Fig. 4, they will be spaced apart parallel with one another, allowing a space for other parts. This arrangement also enables the walls to be folded into a flat position with the walls 8 and 10 flush, and the walls 9 and 11 also flush. The top 10 has its rear end hingedly connected, as at 18, to the upper edge of the 70 rear wall 7, and the bottom 11 is similarly hinged, as at 19, at its forward edge to the lower edge of the front wall 6, whereby the top can swing open rearwardly, while the bottom can be swung open forwardly. Thus, 75 in folding the box, when the walls are folded together, the top can be swung against the outer side of the rear wall 7, while the bottom can be swung across the outer side of the front wall 6.

The side edges of the top 10 and bottom 11 are provided with beads 20 which may be stiffened by wires therein, and when the top and bottom are in closed position, such beads overlap the edges of the side walls 8 80 and 9 on the outside, and thereby not only stiffen the side edges of the top and bottom, but also preventing the side walls from bulging outwardly. By the provision of the hinges having the hinge rods therein, and 85

the beads 20, all corners of the crate are reinforced and stiffened, to withstand rough handling.

In order to hold the top and bottom closed, 5 each of them is provided at its free edge with hinge butts 21, and the upper edge of the front wall 6 and lower edge of the rear wall 7 are provided with alternate hinge butts 22 with which the hinge butts 21 register when the top and bottom are closed. 10 Rods 23 are then slid through the registering hinge butts 21 and 22, to securely hold the top and bottom closed, and to stiffen and reinforce the corresponding corners of the 15 crate. Each rod 23 preferably has a finger piece or eye 24 at one end for convenience in inserting and withdrawing the rod.

The upper and lower edges of the side walls 8 and 9 are provided with flanges or 20 lips 25 extending inwardly at an angle, serving to stiffen said edges of the side walls, as well as to retain the ordinary egg-cell fillers 26 within the crate, especially when it is folded. These fillers 26 are of 25 well known form, comprising partitions crossing one another and foldable together, and these fillers are disposed one above the other in a tier with horizontal partitions 27 between the fillers for supporting the eggs in 30 the cells. These fillers are used when the crate is employed for shipping eggs, and the flanges 25 overlap the upper and lower fillers to retain them in place, although the fillers can be removed by hand in emptying the 35 crate. Then, in placing the fillers back into the crate after it has been emptied, the partitions 27, instead of being between the fillers, are inserted adjacent to one wall of the crate, being shown in Fig. 4 as being disposed against the rear wall. The crate can 40 then be folded, the top and bottom being swung outwardly against the rear and front walls, and the hinges 12 and 13 being moved toward one another. The fillers 26 will fold 45 with the walls, and will be retained in the space between the walls, as provided by the

flanges 14 and 16, and the flanges 25 are of substantially the same width as the flanges 14 and 16 to close said space at the top and bottom, whereby to retain the fillers 26 and 50 partitions 27 within the folded crate. When the crate is thus folded, it will require but little space in storing or returning same, and about ten folded crates can be stored or shipped in the space required for a single 55 crate when erected. Those ends of the flanges 25 adjacent to the flanges 14 and 16 terminate short of the said flanges 14 and 16 and the corresponding walls 6 and 7, to permit the crate to close and the said ends 60 of the flanges 25 to move adjacent to the flanges 14 and 16. The side walls 8 and 9 are preferably provided with handles 28 for convenience in lifting or carrying the crate, and which can be swung downwardly against 65 said walls when not in use.

Having thus described the invention, what is claimed as new is:—

A folding crate comprising four sheet metal walls, said walls being hinged at two 70 diagonally opposite corners, two opposite walls having flanges at their other corners extending at an angle and hinged to the other walls, a top and a bottom each hinged to one of the first named walls, the last 75 named walls having flanges at their upper and lower edges extending inwardly to retain fillers within the crate, and to close the spaces between the walls when they are folded together, those ends of the second 80 named flanges adjacent to the first named flanges terminating short of said first named flanges and the first named opposite walls, and the first named and second named flanges being of substantially the same width, the 85 top and bottom being seatable against the second named flanges, when they are in closed position.

In testimony whereof I hereunto affix my signature.

CASWELL LEE LEONARD.
